UNITED STATES PATENT OFFICE

MARTIN HARPER, OF STRAND, LONDON, ENGLAND

MEANS FOR WINDING ENDLESS CINEMATOGRAPH FILMS AND THE LIKE

Application filed November 2, 1928, Serial No. 316,833, and in Great Britain July 9, 1928.

This invention relates to means for winding endless cinematograph films and the like.

The object of the present invention is to provide an improved form of drum or reel on which the film or the like can be continuously wound and unwound in the form of a coil, and which can be operated with a minimum of friction and power.

According to this invention the drum or reel comprises two plates, one made in the form of a flat ring, spaced apart by means of rollers carried by adjustable centres in the plates and arranged near the periphery and at right angles to the plates. Near the periphery of the lower plate are a number of apertures, which allow the upper surfaces of a number of rollers, one for each aperture and carried by adjustable centres mounted beneath the plate, to protrude just above the plane of the plate. These latter rollers extend radially of the plate, and the edges of the film coil rest on these rollers.

Approximately in the centre of the lower plate is an aperture over which a roller is mounted with the lowest part of its surface in the plane of the plate, and an additional roller is carried in an aperture on a tangential extension to the plate.

Secured to the underside of the lower plate is a bracket for adjustably attaching the drum or reel to the projection apparatus, and one or more pins are radially adjustable in slotted guides in the plate, or are otherwise radially adjustable.

My invention is illustrated in the accompanying drawings in which:—

Fig. 1 is a plan view of a drum or reel made in accordance with my invention, part of the upper plate being broken away; and

Fig. 2 is a section taken on the line 2—2 of Fig. 1.

In these drawings the plates 1, 1a are each provided with a series of oppositely disposed adjustable centres 2, 2, between each opposite pair of which is mounted a roller 3.

Mounted below the plate 1 in brackets 4, having adjustable centres 5, are a series of rollers 6, whose upper surfaces protrude through apertures 7 in the plate.

Approximately in the centre of the lower

plate 1 is an aperture 8 above which is mounted a roller 9 carried by adjustable centres 10 in brackets 11, the roller being so mounted that when the drum or reel is mounted on the apparatus, the said roller is directly above the gate and the lowest part of its surface is in the plane of the lower plate 1.

One or more pins 12 are adjustable in radial slots 13 in the lower plate 1, being secured in position by a wing nut 14. The outer ends of the radial slots 13 extend beyond the periphery of the rollers 3.

On the periphery of the lower plate 1 I provide a tangential extension 15 having an aperture 16 in which is mounted a roller 17 on adjustable centres 18.

Secured to the underside of the lower plate 1 is a bracket 19 for adjustably securing the drum or reel to the projection apparatus.

The method of winding the film in a coil on this improved drum or reel is as follows:—

The beginning of the film is passed downwardly through the aperture 8 and thence through the projection apparatus and the end is left free. The reel of film above the lower plate is passed over the roller 9 and then with a half-turn vertically around the outside of all of the rollers 3, as shown, in an anti-clockwise direction, the pin 12 having previously been moved to the outer end of the slot 13. As many turns of the film as are necessary are made, the end then passing, with a half-turn horizontally over the roller 17.

The end is then passed over a compensating roller, which is carried by a spring-controlled arm hinged to the base or other suitable part of the apparatus, and the two free ends are then joined together to form an endless coil.

The pin 12 is then moved to the inner end of the slot 13 to ensure that the coil will have the necessary slackness during operation.

It is essential that the drum or reel should be always truly horizontal, otherwise the convolutions of the coil pressing on each other cause the coil to bind, and as it is at times desirable to project with the projection apparatus at an angle, the connection between the plate and the projection apparatus

is such that the plate can be adjusted so as always to maintain a horizontal position.

The drawings show the plates forming the drum or reel as circular. It has been found, 5 however, that varying temperatures affect the base now being used for non-inflammable films and at certain temperatures such base will form sharp angles and therefore will not keep to an absolute circle round the rollers.

10 This has been found to accentuate itself when a large footage of about 1,000 feet or over is used and in such cases I find that it is preferable to vary the form of such a reel from a circular plate to an elliptical or other 15 curved plate or to an oblong plate with curved ends.

I claim:—

1. Means for winding endless cinematograph films and the like comprising a film 20 carrying drum, two plates spaced apart by means of rollers arranged near the periphery and at right angles to the plates, centres for such rollers mounted in the plates, an aperture in the lower plate, a roller mounted 25 parallel with the lower plate, and with the lowest part of its surface in the plane of the plate, centres for said roller mounted on said lower plate, a tangential extension to said lower plate, an aperture in said extension, a second roller mounted parallel with the lower plate, and with the 30 lowest part of its surface in the plane of the plate, centres for said roller mounted on said extension, and means for adjustably attaching the film-carrying drum or reel in a horizontal position to a projection apparatus.

2. Means for winding endless cinematograph films and the like comprising a film carrying drum, two plates spaced apart by means of rollers arranged near the periphery 40 and at right angles to the plates, adjustable centres for such rollers mounted in the plates, an aperture in the lower plate, a roller mounted parallel with the lower plate, and with the lowest part of its surface in the plane of the 45 plate, adjustable centres for said roller mounted on said lower plate, a tangential extension to said lower plate, an aperture in said extension, a second roller mounted parallel with the said extension and in said aperture, adjustable centres for said second roller mounted on said extension, and means for adjustably attaching the film-carrying drum or reel in a horizontal position to a projection apparatus.

55 3. Means for winding endless cinematograph films and the like comprising a film carrying drum, two plates spaced apart by means of rollers arranged near the periphery and at right angles to the plates, adjustable 60 centres for such rollers mounted in the plates, an aperture in the lower plate, a roller mounted parallel with the lower plate, and with the lowest part of its surface in the plane of the 65 plate, adjustable centres for said roller mounted on said lower plate, a tangential ex-

tension to said lower plate, an aperture in said extension, a second roller mounted parallel with the said extension and in said aperture, adjustable centres for said second roller mounted on said extension, a radial slot 70 in the lower plate, a pin adjustable in said slot, and means for adjustably attaching the film-carrying drum or reel in a horizontal position to a projection apparatus.

4. Means for winding endless cinematograph films and the like comprising a film carrying drum, two plates spaced apart by means of rollers arranged near the periphery and at right angles to the plates, adjustable centres for such rollers mounted in the plates, an aperture in the lower plate, a roller mounted parallel with the lower plate, and with the lowest part of its surface in the plane of the plate, adjustable centres for said roller mounted on said lower plate, a tangential extension to said lower plate, an aperture in said extension, a second roller mounted parallel with the said extension and in said aperture, adjustable centres for said second roller mounted on said extension, a radial slot in 80 the lower plate, a pin adjustable in said slot, a series of apertures in said lower plate near to the periphery thereof and a roller mounted in adjustable centres below each aperture and arranged radially of the said lower plate with its upper surface protruding through said aperture, and means for adjustably attaching the film-carrying drum or reel in a horizontal position to a projection apparatus.

In testimony whereof I have hereunto set my hand, this nineteenth day of October, 1928.

MARTIN HARPER.
